CLOSET CHAIR

Filed Oct. 4, 1926

UNITED STATES PATENT OFFICE

EUGENE A. ZUNDEL, OF CHICAGO, ILLINOIS

CLOSET CHAIR

Application filed October 4, 1926. Serial No. 139,445.

The invention relates to closet chairs and more particularly to the type of chair embodying a closet seat and a chair seat, so that it may at times serve the purpose of an ordinary chair.

An object of the invention is to provide a closet chair which is supported against lateral movement by its engagement with the closet bowl.

Another object of the invention is to provide a closet chair construction which will facilitate assembly and reduce the cost of manufacture.

The invention further consists in the several features hereinafter set forth and more particularly defined by the annexed claims.

In the accompanying drawings:

Fig. 1 is a side elevation of a closet chair constructed in accordance with the invention and mounted over a closet bowl, both seats of the chair being in their lowered positions;

Fig. 2 is a rear elevation thereof, parts of the closet bowl being broken away and parts being shown in section;

Fig. 3 is a sectional view of the chair taken on the line 3—3 of Fig. 1;

Fig. 4 is a similar view showing a modified form of the chair structure;

Fig. 5 is a bottom view of the chair; and

Fig. 6 is a detail perspective view showing a seat hinge for the chair.

In these drawings 10 indicates a water closet bowl having the usual spaced apertures 11 at its rear portion opening at the upper surface of the bowl. A seat frame 12, preferably of heavy sheet metal, includes a horizontal rear shelf 13 for disposition above the rear portion of the bowl and having depending flanges 14 at its sides which extend forwardly to form laterally resilient arms 15 having leg-receiving loops of sockets 16 formed integrally at their forward ends. The rear ends of the flanges 14 are bent inwardly to form vertical flanges 17, against which rear legs 18 are secured by screws 19, the legs extending above the seat frame. The loops or sockets 16 at the forward ends of the arms 15 receive the reduced upper ends of front legs 20, and resilient seat bumpers 21 are mounted in the upper ends of the loops.

A pair of hinge plates 22 are each secured to the outer side faces of the rear legs 18 by screws 23 to form forwardly projecting arms. A chair seat 24 is provided with aligned pins 25 at opposite sides of its rear portion pivotally mounted in the hinge plates 22, and a subjacent closet seat 26 has the opposite sides of its rear portion provided with upwardly projecting ears 27 secured to the seat by screws 28 and pivotally suspended at their upper ends on the pins 25. A back 29 is secured to the upper ends of the rear legs 18 by screws 30. The seats 24 and 26 and the back 29 may be made from the same pattern to facilitate manufacture, the seat 24 and back being substantially identical and preferably caned for greater comfort and better appearance.

The forward end of the closet seat 26 has secured thereto a curved depending apron 31, which is provided with ears 32 at its upper edge receiving screws 33 driven into the lower surface of the seat. The apron 31 and arms 15 conceal the upper rim of the bowl and together present the appearance of a continuous curved band. The seat frame and apron may be white enameled or otherwise suitably finished.

In the modified form of the invention shown in Fig. 4 the seat frame 12 has its resilient arms 15' extending forwardly and meeting integrally to form the apron 31', in which case the front legs 20 of the seat are mounted in short tubes or sockets 16' welded to the inner face of the arms.

The shelf 13 of the seat frame 12 has secured thereto depending pins 34 which register with and enter the apertures 11 in the seat bowl so as to properly position the chair thereover and render it rigid. The shelf of the seat frame is preferably spaced somewhat from the upper face of the bowl to provide accessibility for cleaning. In placing the seat over the bowl the forward ends of the arms 15 are sprung apart and thereby add rigidity to the chair irrespective of the removability of the front apron, which is provided for sanitary reasons. The use of cross bracing for the legs is thus rendered unnecessary, which simplifies the construction of

the chair and reduces the cost of manufacture.

When the two seats are raised the front of the bowl is entirely exposed, thus preventing any insanitation. In other words, there is no part of the chair that obstructs the free use of the bowl. There is no place to catch urine and in a short time be not only insanitary but to emit an offensive odor. 15 Also when the two seats are raised the particular construction of the hinge throws the seats up to a position that leaves the entire back of the chair and the bowl accessible for cleaning, which is a very great sanitary feature.

15 What I claim as new and desire to secure by Letters Patent is:

1. In a closet chair, the combination, with a closet bowl having apertures at its rear portion opening upwardly, of a chair frame disposed over said bowl and having supporting legs, and depending members at the rear portion of said frame entering said apertures to position said frame with respect to the bowl and to support said frame against lateral movement.

2. In a closet chair, the combination, with a closet bowl, of a chair frame including legs and having resilient side members engageable with the sides of the bowl, and means carried by said frame engageable with the bowl at its rear portion for positioning said frame thereon.

3. A closet chair comprising a chair frame adapted to be disposed over a closet bowl and including supporting legs, and depending members carried at the rear portion of said chair frame and engageable with the rearward portions of said bowl for positioning said chair frame on said bowl against lateral and forward displacement.

4. A closet chair comprising a chair frame including resilient side portions adapted to enclose and engage the sides of a closet bowl, supporting legs carried by said chair frame, and a closet seat mounted on said chair frame.

5. A closet chair comprising a U-shaped chair frame including laterally resilient arms adapted to engage the sides of a closet bowl, depending pins carried by said frame for engaging the rear portion of said bowl, supporting legs carried by said frame, and a closet seat mounted on said frame.

6. In a closet chair, the combination of a chair frame including forwardly projecting bendable metal side members having loops formed at their forward portions to provide downwardly-opening leg-receiving sockets, and front legs carried in said sockets.

7. In a closet chair, the combination, with a closet bowl, of a chair frame including legs and having displaceable side members simultaneously engageable with and urged against opposite sides of the bowl, and means

carried by said frame engageable with the bowl at its rear portion for positioning the frame thereon.

8. In a closet chair, the combination of a U-shaped metal frame adapted to be disposed over a closet bowl and including a rear transverse portion and flanged portions depending therefrom and extending forwardly to form arms, front legs secured to the forward portions of said arms, and rear legs secured to the rear portion of said metal frame.

In testimony whereof I affix my signature.

EUGENE A. ZUNDEL.
